UNITED STATES PATENT OFFICE.

RUDOLPH KOEHLER, OF ST. LOUIS, MISSOURI.

DESIGN FOR A VEHICLE-CARRIED TRAFFIC-SIGNAL CASING.

Application filed September 6, 1921. Serial No. 498,921. Term of patent 14 years.

To all whom it may concern:

Be it known that I, RUDOLPH KOEHLER, a citizen of the United States of America, residing in the city of St. Louis and State of Missouri, have invented a new, original, and ornamental Design for a Vehicle-Carried Traffic-Signal Casing or Similar Article, of which the following is a specification, reference being had to the accompanying drawings, forming part thereof.

Figure 1 is a front elevation of a vehicle carried traffic signal casing showing my new design.

Figure 2 is a rear elevation.

Figure 3 is a side elevation.

I claim:

The ornamental design for a vehicle carried traffic signal casing, as shown.

RUDOLPH KOEHLER.
